IMPROVEMENT IN SHIFTING SEATS FOR CARRIAGES.

CHRISTIAN K. MELLINGER, OF MANOR TOWNSHIP, PENNSYLVANIA.

Letters Patent No. 59,920, dated November 20, 1866.

SPECIFICATION.

TO ALL WHOM IT MAY CONCERN:

Be it known that I, CHRISTIAN K. MELLINGER, of Manor township, in the county of Lancaster, and State of Pennsylvania, have invented a new and improved mode for constructing Shifting Seats for Carriages; and I hereby declare that the following is a full and exact description thereof, reference being had to the accompanying drawings and the letters of reference marked thereon, making a part of this specification, in which—

Figure 1 is a perspective view of a common farmer's carriage-box, with my improved shifting seat in place.

Figure 2 is a side view of a three-posted box with the seat thrown forward, the dotted lines showing the position of the seat when thrown back.

Figures 3 are diagrams to illustrate the construction and operation of the combined sides or supports of the seat.

Figure 4, seat and drop-lazy-back, O.

The object of my invention is to construct or supply a simple shifting seat, which is easily shifted, and that will set firm, and be durable and cheap withal, and clearly to obviate all dangers of catching the clothing or impeding in any manner the getting in or out of the carriage from the back seat. This is accomplished by the following simple device, which I will now proceed to describe, to enable others skilled in the art to make and use my invention.

Each side of the seat-board or end is supported by the combined pieces B or top, the straight and curved braces C D, and bottom piece A. The latter is firmly bolted to the floor or side beam at the bottom of the carriage, and is stationary. The upper side of A is provided with boxes or deep slots, having such a bevel on the ends as to adapt them to the slope or curve of the braces when turned to the desired extent back or forward; these braces are held by a stout pin or pivot, P, within the slots or boxes, a' a'' and b' b'', at both ends, the slot b' b'' being, of course, on the under side of the top piece B. These boxes a' a'' are similar in bevel to those of b' b'' in their reversed position. Thus constructed, each end of the seat, supported by the top and braces, working in unison on their pivots, P, within the boxes or slots, on the fixed piece A, will admit the seat to be pushed forward to the position shown by figs. 3 with ease, removing all obstruction from the centre of the carriage, and admit ladies and children to enter on the side of the vehicle and occupy the back seat with the greatest ease. When seated, by a slight pull the seat is drawn back, as indicated by the dotted lines. Said braces and top and bottom pieces may be made of wrought or cast iron, or of wood, (provided it is sufficiently stout.) It will be noticed that the braces C D, held by a stout pivot within the boxes, are stayed and prevented from yielding laterally, while the bevel of the box or slot comes square in contact with the edge of the brace within the slot, yielding a firm support and securing the stability against any weight or pressure vertically. I find iron of an inch square, with boxes or slots to receive the iron braces, made one inch wide and five sixteenths thick, sufficiently strong; the pivots eleven inches apart, and the straight brace, c, say sixteen inches long. The brace I may be more or less curved; a radius of twelve inches gives a good curve, and throws the seat as shown in the diagram, figs. 3. The straight brace, I incline forward and backward from its centre, so as to be 40° above the horizontal line drawn through the pivot in either position, thus moving in a curve of 100° from one position to the other, as shown. The height and throw of the seat may of course be varied. Simple, durable, and satisfactory as this device will prove to be, I am well aware of various devices for shifting and folding over seats in carriages, so that the object I aim at is not new; but my mode of accomplishing the same, by a specific arrangement in the construction of the slots and arms, I believe to be novel and highly useful. I would say that the object of the curved brace D is to afford room for the knees of those occupying the back seat, especially when closed by leather or otherwise, as well as to yield a firmer contact within the slot and support of the seat above by lengthening said line of contact within the slots a'' and b''. The top piece B may also be provided with horizontal projections, G, turned inward, for additional supports to the seat-board. There is a block Q, with notch or shoulder to support the braces on each side, held by a pivot, P, so as to fold forward over the seat. (The hind seat, adapted for women, is usually made a little lower than that of the front seat, or driver's.) therefore do not claim a shifting seat, nor simply the slotted top and bottom pieces or braces, separately considered, as such may be shown combined in a variety of forms for various purposes.

What I claim as my invention, and desire to secure by Letters Patent, is—

The specified combination and arrangement of the top and bottom pieces A B, braces C D, held by pivot P, within the boxes or slots a' a'' and b' b'', bevelled or constructed and operating in the manner and for the purpose specified.

CHRISTIAN K. MELLINGER.
